UNITED STATES PATENT OFFICE

171,440

GARTER CLASP

John J. Chisholm, Worcester, Mass.

Application April 3, 1953, Serial No. 24,351

Term of patent 7 years

(Cl. D17—3)

To all whom it may concern:

Be it known that I, John J. Chisholm, a citizen of the United States, residing at Worcester, in the county of Worcester and State of Massachusetts, have invented a new, original, and ornamental Design for a Garter Clasp, of which the following is a specification, reference being had to the accompanying drawing, forming part thereof.

Fig. 1 is a view in front elevation of a garter clasp, showing my new design; and

Fig. 2 is an edge view thereof.

I claim:

The ornamental design for a garter clasp, as shown.

JOHN J. CHISHOLM.
